UNITED STATES PATENT OFFICE.

BERNARD O. SMITH, OF OELWEIN, IOWA.

DESIGN FOR AN INTAKE-MANIFOLD FOR GASOLENE-ENGINES.

46,034.

Specification for Design.

Patented June 30, 1914.

Application filed April 11, 1914. Serial No. 831,338. Term of patent 14 years.

To all whom it may concern:

Be it known that I, BERNARD O. SMITH, a citizen of the United States, residing at Oelwein, in the county of Fayette and State of Iowa, have invented a new, original, and ornamental Design for an Intake-Manifold for Gasolene-Engines, of which the following is a specification.

Reference is had to the accompanying drawing, in which:—

Figure 1 is a perspective view of an intake manifold for gasolene engines, showing my new and ornamental design. Fig. 2 is a rear elevation of the same.

In the drawing, 1—1 designates substantially semi-circular branches connected by a substantially straight body portion or member 2, having a neck 3 which extends from the straight connecting member 2 in the opposite direction from the semi-circular branches 1. The semi-circular branches, which are united with the terminals of the

connecting member 2 at a point intermediate of their ends, have laterally deflected longitudinally alined terminals 4 provided with arcuate flanges 5. The branches 1 are also provided with laterally projecting polygonal lugs 6 extending from the branches in the opposite direction from that in which the deflected terminals project. The neck 3 is provided at its outer end with a bolting flange 7.

I claim:

An ornamental design for an intake manifold for gasolene engines substantially as shown and described.

In testimony, that I claim the foregoing as my own, I have hereto affixed my signature in the presence of two witnesses.

BERNARD O. SMITH.

Witnesses:

JOHN W. SIGGERS,
E. G. SIGGERS.
